CLAIM

The ornamental design for a wide front docking cradle, as shown and described.

DESCRIPTION

FIG. 1 is an isometric view of a wide front docking cradle showing our new design;
FIG. 2 is a front elevational view thereof;
FIG. 3 is a right elevational view thereof;
FIG. 4 is a left elevational view thereof;
FIG. 5 is a top plan view thereof;
FIG. 6 is a bottom plan view thereof;
FIG. 7 is a back side isometric view thereof; and,
FIG. 8 is an underside isometric view thereof.
